DOOR CHAIN LOCK

Louis G. Bobrowski, Berlin, Conn., assignor to The
Stanley Works, New Britain, Conn.

Filed Sept. 8, 1971, Ser. No. 178,854

Term of patent 14 years

Int. Cl. D8—07

U.S. Cl. D8—131

FIG. 1

FIG. 2

FIG. 3

FIG. 4

FIG. 5

FIG. 1 is a perspective view looking upwardly towards the front of one form of a door chain lock showing my design;

FIG. 2 is a perspective view looking downwardly towards the rear of the door chain lock shown in FIG. 1;

FIG. 3 is a perspective view looking upwardly towards the front of another form of a door chain lock showing my design;

FIG. 4 is a perspective view looking downwardly towards the rear of the door chain lock shown in FIG. 3; and

FIG. 5 is a front elevational view of a lock housing of the door chain lock shown in FIG. 3.

The chain has been broken away for convenience of illustration.

I claim:

The ornamental design for a door chain lock, as shown.
